UNITED STATES PATENT OFFICE.

CHRISTIAN F. BACHLER, OF PHILADELPHIA, PENNSYLVANIA.

STEAM AND WATER BOILER.

Application filed April 30, 1919. Serial No. 293,777.

To all whom it may concern:

Be it known that I, CHRISTIAN F. BACHLER, a citizen of the United States, residing in the city and county of Philadelphia, State 5 of Pennsylvania, have invented a new and useful Steam and Water Boiler, of which the following is a specification.

My invention consists of a novel construction of a steam and water boiler embodying a water jacket, a series of U-shaped water-receiving tubes in the body of the boiler communicating with said jacket, a central fuel magazine, a fuel inlet in the dome of said body, a fuel directing chute connected 15 with said dome and extending inclined from said inlet to said magazine, means for connecting said chute with said magazine, a closure for said magazine mounted on the top thereof, and a baffle plate in the body around 20 the upper end of said magazine connected therewith, said tubes being below said baffle plate whereby the heat acts on the vertical portions of said tubes and the lateral bends thereof before escaping into the dome, while 25 the central magazine is supported in the body by a collar on said fuel chute, said magazine supporting also the closure therefor and the baffle plate.

To the above ends my invention consists 30 of a novel construction of a steam and water boiler wherein the maximum available space within the water jacket is occupied by water tubes collocated in a novel manner which are efficiently subjected to the products 35 of combustion, said boiler being adapted to be used as a magazine feed or as a base burner, provision being further made for any of the boiler tubes to be readily accessible according to requirements, at all times 40 for the purpose of inspection, replacement or repair.

For the purpose of illustrating my invention, I have shown in the accompanying drawings one form thereof which is at present preferred by me, since the same will be 45 found to give satisfactory and reliable results, although it is to be understood that the various instrumentalities of which my invention consists can be variously arranged and organized and that my invention is not 50 limited to the precise arrangement and or-

ganization of these instrumentalities as herein shown and described.

Figure 1 represents a vertical sectional view of a steam and water boiler embodying my invention, the section being taken on the line 1—1 Figure 2.

Figure 2 represents a transverse section on line 2—2 Figure 1.

Similar numerals of reference indicate corresponding parts in the figures.

Referring to the drawings.

1 designates the body of my steam and water boiler, the same having a base 2 of any suitable construction, which carries the grate 3 of any conventional type. On the base 2 is supported the annular water jacket 4, which comprises the outer shell 5 and the inner shell 6, said shells being suitably supported upon the annular base flange 7, and secured 70 thereto by rivets, bolts or other fastening devices 8. The upper portion of the water jacket formed by the shells 5 and 6 is closed by the upper ring 9, which is secured to the shells 5 and 6 by the fastening bolts 10 which pass through said shells and ring and so is firmly held in position. Upon the upper portion of said ring or water jacket, I locate the dome 11, which is secured in place by the stud bolts 12 which may be two or 80 four in number, it being apparent that upon the removal of the nuts from the bolts 12 the dome can be readily lifted from the top of the boiler for the purpose of obtaining access to the interior. The upper portion of 85 the dome is provided with a neck or chamber 13, having the door 14 leading thereto, said chamber having a flue or outlet 15 for the exit of the products of combustion.

16 designates a door leading to the chute 90 17, which communicates with the central magazine 18, which is closed by the door 19 which can be actuated from the exterior by the handle 20. The chute 17 which begins at the inlet in the dome 11 extends downwardly from the latter in inclined direction to the top of the magazine where its lower end is provided with a collar 17^x which encircles said top and is secured thereto by bolts or other suitable means, thus firmly sustaining 95 the chute in position.

It will be seen also that the central maga-

zine is held suspended in position on said chute 17 by said collar, the securing bolts passing through said collar into the wall of the magazine as hereinbefore referred to, 5 it being seen further that the magazine is utilized to form the support also for the connection of the door 19 and the baffle plate 31.

21 and 26 designate a series of circulating 10 or U tubes which are expanded at their upper and lower ends 22 and 23 into said inner shell 6, it being noted that directly opposite to the ends 22 and 23 of said tubes the plugs or closures 24 and 25 respectively 15 are located in the outer shell 5, whereby access can be readily had to the end of any desired tube at the outer shell when the respective plugs are removed.

It will be apparent that the long U-shaped 20 tubes 21 project inwardly and extend longitudinally for a great portion of their length in close proximity to the magazine 18, their lower ends 23 entering the water jacket 4 at a point near the lower portion of the combustion chamber 30, while their upper ends 22 enter the inner shell 6 at a point in proximity to the water line, so that a rapid 25 and effective circulation will be at all times maintained within the boiler.

30 It will be seen from Figure 2 that when the long tubes 21 are in position there is a considerable space or area between them which is ordinarily not utilized, but in my present invention, by the employment of the 35 intervening shorter U-tubes 26, I utilize this space or area so that the long and short tubes 21 and 26 are arranged in staggered order so as to substantially fill the upper portion of the combustion chamber 30 whereby a very considerable tubular area 40 is subjected to the action of the heat units and products of combustion so that practically the entire area within the water jacket 4 is occupied by the staggered tubes 21 and 45 26 which are effectively subjected to the effect of the products of combustion.

27 designates a series of plugs, see Figure 2, which are located in alignment with the ends of the shorter tubes 26, whereby access 50 can be readily had to the ends of said tubes for the purpose of inspection or repair.

28 designates an opening through the lower portion of the water jacket, which is closed by the door 29, whereby access can be had and fuel supplied to the lower portion 55 of the combustion chamber 30, it being apparent that my device can consequently be used as a magazine burner or base burner.

31 designates a deflector attached to the 60 upper portion of the magazine 18 and having the holes 32 therethrough as a baffle plate to cause the heat to act directly on the vertical portions as well as the terminal lateral bends of the several U-shaped tubes be-

fore escaping into the dome, it being evident 65 that said tubes are below said baffle plate.

It will be apparent from the foregoing that in my invention, I dispense with a crown sheet and thereby eliminate the liability of explosions since it is well known 70 that a great majority of boiler explosions are due to the collapse of the crown sheet,

It will further be apparent, that a very effective maximum area is subjected to the 75 action of the heat units and products of combustion, as practically the entire area within the water jacket is occupied by the staggered U tubes 21 and 26, said tubes 21 extending from the water jacket inwardly in radial lines.

When it is desired to obtain access to any 80 of the tubes for any purpose it can be readily effected by the removal of the plugs 24, 25, or 27, and if it is desired to obtain access to the interior of the boiler, this can be readily effected by the removal of the nuts from the bolts 12 when the dome is disconnected from the ring and may then be removed.

By the employment of the magazine 18 and lower door 29 either can be used for firing, so that my invention is adapted for use 90 as a magazine burner or a base burner, according to requirements.

While I have denominated for the purpose of distinction the tubes 26 as short, and the tubes 21 as long, said tubes 26 are turned into the heating chamber to a less extent than said tubes 21, and so the former are adapted to occupy the spaces between the latter, whereby said spaces are utilized to receive said tubes 26 with the advantage hereinbefore stated.

It will now be apparent that I have devised a novel and useful construction of a steam and water boiler which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention what I claim as new and desire to secure by Letters Patent, is:

In a boiler of the character stated, a 120 body having a water jacket, a dome having a fuel inlet therein, means for connecting said dome with said body, a central magazine, a closure for said magazine mounted on the top thereof, means for operating said closure from the exterior of said dome, a fuel directing chute connected with said dome and extending inclined from said in-

let to said magazine, a collar on the inner end of said chute with which said magazine is connected and by which it is sustained in said body, a baffle plate in the body around 5 the upper end of said magazine, and connected therewith, and a series of U-shaped water receiving tubes between the base and

dome of the boiler surrounding said central magazine below said baffle plate and communicating with said water jacket.

CHRISTIAN F. BACHLER.
